(57) **CLAIM**

The ornamental design for a percussion drive, as shown and described.

DESCRIPTION

FIG. 1 is a top front perspective view of a percussion drive showing our new design;

FIG. 2 is a bottom rear perspective view thereof;

FIG. 3 is a front elevational view thereof;

FIG. 4 is a right-side elevational view thereof;

FIG. 5 is a left-side elevational view thereof;

FIG. 6 is a top plan view thereof;

FIG. 7 is a bottom plan view thereof;

FIG. 8 is a back elevational view thereof; and,

FIG. 9 is a detail view of area 9 in FIG. 1.

The broken lines showing the tool body in FIGS. 1-9 are included for the purpose of showing environmental structure and form no part of the claimed design. The percussion drive is shown with a symbolic break in its length in FIGS. 4-7. The appearance of any portion of the article between the break lines forms no part of the claimed design.
